REFRIGERATING APPARATUS

Lawrence A. Philipp, Detroit, Mich., assignor, by
mesne assignments, to Nash-Kelvinator Cor-
poration, Detroit, Mich., a corporation of Mary-
land

Application April 15, 1932, Serial No. 605,465

31 Claims. (Cl. 62—115)

This invention relates to refrigeration and more particularly to an improved method and apparatus for controlling temperatures.

One of the objects of my invention is to provide a refrigerating apparatus for cooling a plurality of zones and to provide an improved arrangement for maintaining a temperature differential between said zones.

Another object is to provide a refrigerating apparatus of the type which includes primary and secondary refrigerating systems and to provide an improved method for maintaining a temperature differential between said systems.

Another object of my invention consists in an improved method of controlling temperatures in the primary and secondary systems of the aforesaid apparatus.

A further object of my invention is to provide a refrigerating apparatus of the type which includes an intermittently operated primary refrigerating system and a secondary refrigerating system arranged in heat exchange relation with the primary system for condensing evaporated refrigerant in the secondary system and an improved arrangement for controlling the operation of the primary system.

A still further object consists in an apparatus for cooling liquids and the provision of improved means for preventing the freezing of the liquids during normal or abnormal operation of the apparatus.

Further objects and advantages of the present invention will be apparent from the following description, reference being had to the accompanying drawings, wherein a preferred form of the present invention is clearly shown.

In the drawings:

Fig. 1 is a diagrammatic illustration of a refrigerating apparatus for cooling circulating water, embodying features of my invention;

Fig. 2 is a front view in elevation of a refrigerating apparatus embodying features of my invention;

Fig. 3 is an enlarged view in cross section taken along the line 3—3 of Fig. 2;

Fig. 4 is a view in cross section of a modified form of refrigerating apparatus; and

Fig. 5 is a diagrammatic illustration of my improved refrigerating system in connection with a soda fountain.

In providing a refrigerating apparatus for cooling circulating water for drinking purposes, it has been found that some means should be provided for maintaining the element which cools the circulating water within a certain tempera-

ture range so that the water may be cooled to the desired temperature at which it is palatable and also so that the temperature of the water is not reduced to a temperature which would cause the freezing thereof and the possible destruction of the apparatus. In water coolers of the type which include an intermittently operated refrigerating apparatus for cooling the circulating water it has been found by experience that the various types of mechanism employed for controlling the operation of the apparatus or for controlling the admission of refrigerant to the cooling element of the apparatus are very likely to become faulty in operation which causes abnormal operation of the apparatus. It has also been found that the controlling mechanisms are very likely to get out of proper adjustment or that they are improperly adjusted by someone unfamiliar with the operation of the apparatus. This abnormal operation of the apparatus either results in the drinking water not being cooled sufficiently or that it is cooled to the point which causes freezing thereof and the consequential destruction of the system.

In accordance with my invention I make provisions for maintaining the temperature of the water substantially constant and at the desired temperature which is above the freezing point of water. This is accomplished by providing a refrigerating apparatus of the type having primary and secondary refrigerating systems arranged in heat exchange relation, with the primary system being employed for condensing evaporated refrigerant in the secondary system, and the secondary system being used for cooling the circulating water. In order to control the temperature in the secondary system I have provided in the secondary system a body of liquid, preferably water, congealable by the evaporation of refrigerant in the secondary system. This congealable liquid is so arranged in the secondary system that the evaporated refrigerant must pass therethrough before being condensed by the cooling action of the primary system. By this arrangement, the body of liquid gradually becomes congealed and when in this form limits the amount of evaporated refrigerant passing therethrough to be condensed by the primary system. When this takes place, some of the evaporated refrigerant in the secondary system is condensed by the body of liquid in its congealed form. By limiting the amount of refrigerant condensed by the primary system and by serving as a condenser for some of the vaporized refrigerant, the body of water never becomes frozen into a solid mass but

remains either in the form of a liquid or in the form of slush. Since the body of water in the secondary system which is cooled by the secondary system never freezes into a complete solid, it necessarily follows that the circulating drinking water is always maintained at a temperature above its freezing point.

My invention is also applicable to household refrigerators. In this embodiment of the invention the primary system is maintained within predetermined low temperature limits for freezing ice cubes or the like and the secondary system is utilized for cooling circulating air in the food storage compartment in the usual manner. Preferably the cooling element of the secondary system is maintained at a temperature which is above the freezing point of water so as to prevent the formation of frost on said element by moisture deposited thereon from the circulating air. This avoids the necessity of periodically defrosting the element which cools the circulating air.

A refrigerating apparatus for cooling circulating water is shown in Fig. 1 diagrammatically represented as including a primary refrigerating system 20 and a secondary refrigerating system 22 arranged in heat exchange relation with the primary system for condensing evaporated refrigerant in the secondary system. The primary system comprises in general an intermittently operated condensing element 24 and a cooling element 25 which is used for condensing evaporated refrigerant in the secondary system. The secondary system is employed for cooling circulating water which passes through a water cooling coil 27 and comprises in general a vaporizing chamber 28 formed by a metallic tank-like member 29. Suitable insulation 31 is interposed between the metallic member 29 and an outer cover 33. Within the vaporizing chamber there is provided a body of liquid refrigerant, the level of which I have indicated at 35, the water cooling coil 27 which is located below the level of refrigerant, cooling element 25 which provides a condensing zone for evaporated refrigerant, and a body of water, the level of which I have indicated at 37. This body of water is adapted to maintain a temperature differential between the refrigerating systems to prevent the freezing of water in coil 27 and also prolongs the "off phase" of the refrigerating cycle of the intermittently operated primary system in a manner about to be described.

Any suitable condensing element may be used for supplying refrigeration to the cooling element 25. As herein shown, I provide a condenser 40, liquid refrigerant receiver 41, compressor 43, and motor 44 for operating compressor 43. The compressor 43 withdraws vaporized refrigerant from the cooling element 25 through a vapor conduit 47, compresses the gaseous refrigerant and delivers it to the condenser 40 wherein it is liquefied and from which it passes to receiver 41. Liquid refrigerant is supplied to the cooling element 25 through a liquid conduit 49 under the control of an expansion valve 50. Preferably the expansion valve is thermostatically controlled in accordance with changes in temperature within the cooling element 25 by means of thermostat bulb 55 which is located preferably in contact with the outlet end of the cooling element 25. Preferably the operation of the primary system is controlled in response to changes in temperature of the body of water within the vaporizing

chamber 28 by means of an automatic switch 60. The switch 60 is operated by means of a bellows 61 which in turn is actuated by a fluid containing thermostatic bulb 62 in the well known manner. Preferably the bulb 62 is disposed within the vaporizing chamber 28 in contact with the body of water so that the fluid contained therein is responsive to changes in temperature of the body of water. The switch 60 is adapted to cut the motor in and out of circuit with the power mains 65 in accordance with changes in temperature of the body of water.

The operation of the device is as follows: Assuming that there is a demand for drinking water, some of the cooled water in the coil 27 will flow out of the discharge end 67 of the coil 27 and water to be cooled will enter the inlet end 69 of coil 27 at a temperature higher than that to which it is to be cooled. The coil 27 may be connected to any suitable pressure system for receiving water and is of such size and shape so that when the water enters the coil and passes therethrough it will, by the time it is ready to leave the water cooling coil, be at its desired temperature. This incoming warm water to be cooled gives up its heat to the liquid refrigerant, causing some of the refrigerant to boil. When this ebullition takes place, evaporated refrigerant must pass through the body of water before passing to the cooling element 25 to be condensed. This evaporation of refrigerant causes the water to gradually become congealed, and in so doing, gradually forms a solid which limits the amount of evaporated refrigerant which may pass through this congealed body and consequently limits the amount of condensation which takes place in the condensing zone adjacent the cooling element 25. When this takes place, the congealed body of water serves as an auxiliary condensing medium and condenses some of the refrigerant evaporated in the secondary system. This condensing action warms up the congealed body and causes a portion thereof to melt and return to its original form of water, the amount depending upon the amount of ebullition which takes place in the secondary system. Thus it will be noted that the evaporation of refrigerant gradually changes the physical properties of the water to a solid. When this takes place the congealed body closes off the passageway for evaporated refrigerant leading to the cooling element 25 in varying proportions. In addition, this congealed body serves as a condenser for some of the evaporated refrigerant and in so doing changes the evaporated refrigerant to a liquid and converts the congealed body partially or entirely to a liquid. This is true whether there are occasional demands for drinking water or whether the evaporation of refrigerant in the secondary system takes place due to the leakage of heat from the exterior of the water cooling apparatus to the body of liquid refrigerant 35. In view of the fact that the same body of refrigerant which cools the body of water 37 also cools the drinking water within the coil 27, it will be readily seen that the drinking water will not be cooled below its freezing point even though there is no demand for drinking water over an appreciable length of time.

Another important advantage in providing a congealable liquid within the secondary system is that the congealed body serves as a hold over which prolongs the "off phase" of the refrigerating cycle of the primary system. This is accom-

plished by controlling the operation of the primary system in response to changes in temperature in the body of water 37 as previously described herein. In view of the fact that the body of water 37 when in congealed form condenses some of the evaporated refrigerant in the secondary system, it will be unnecessary to operate the primary system to perform its condensing action as frequently as it would be necessary without the auxiliary condenser for congealed body of water. Under these conditions, the switch 60 may be set to cut the motor in circuit with the power mains after a major portion or all of the congealed body has returned to its original form of water. It will also be noted that this arrangement permits a wide variation in temperature in the primary system without harm.

Preferably the cooling element 25 of the primary system 20 has sufficient capacity to adequately perform its condensing function but is such that during the "off phase" of the refrigerating cycle of the primary system the element warms up so as to melt or defrost any frost or ice which may be deposited thereon by water vapors in the secondary system. It will also be noted that the warming action of the evaporated refrigerant in the secondary system aids in preventing the formation of ice on the cooling element 25.

30 In the apparatus shown in Fig. 1, I prefer to use methylene chloride as the refrigerant and a fluid, such as water which has a high heat capacity for a small change in temperature, as the congealing liquid. However, it is to be understood that any refrigerant which does not have a deleterious effect on the apparatus when used with a congealable body may be used. Likewise any suitable congealable body of liquid may be used which is of a lighter specific gravity than that of the refrigerant and which is insoluble in the refrigerant.

In Figs. 2 and 3 of the drawings I have shown my invention in connection with a household refrigerator designated 75. The refrigerator 75 comprises in general a cabinet 76 having a food storage compartment 78 formed by an inner metallic liner 79. Suitable insulation such as cork 80 is interposed between the inner metal liner 79 and outer metallic cover 82. The cabinet 76 is provided with an opening 85 in the food storage compartment 78 closed by door 87. Within the food storage compartment there is provided a cooling element 90 which is supplied with refrigerant by a condensing element not shown but which may be the same as the condensing element 24 shown in Fig. 1. The cooling element 90 is disposed within a vaporizing chamber 94 of a secondary refrigerating system 97 for condensing evaporated refrigerant in the secondary system. The vaporizing chamber 94 is formed by a finned casting member 99 and a removable front plate 100. Within the vaporizing chamber I have provided a body of liquid refrigerant, preferably methylene chloride, the level of which I have indicated at 102, and above the body of refrigerant I have provided a body of water, the level of which I have indicated at 104. In this particular embodiment, I have arranged the cooling element 90 for providing an ice freezing zone 106 for freezing ice cubes or the like and have arranged for cooling circulating air in the food storage compartment 78 by means of the secondary refrigerating system 97. The cooling element 90 is preferably of the flooded float controlled type. Any suitable supporting means may

be provided for supporting the cooling element 90 within the secondary system 97. Extending into the ice freezing zone of the cooling element 90 and accessible from the food storage compartment 78 are a plurality of sleeves 110 for the reception of ice making receptacles 112. Below the sleeve 110 and extending into the body of refrigerant 102 in the secondary system, I have provided a sleeve 115 which is somewhat larger than the sleeve 110 for the reception of a tray 10 117. The compartment provided by the sleeve 115 may be used for the storage of food articles at a temperature slightly below the temperature in the compartment 78 and above the temperature in the freezing zone 106. 15

In the apparatus shown in Figs. 2 and 3, the functions of the water and refrigerant in the secondary system are the same as in the apparatus shown in Fig. 1. In this apparatus the refrigerant is evaporated by heat received from the 20 circulating air in the compartment 78. By properly proportioning the amount of water and refrigerant in the secondary system, any desirable temperature differential between the cooling zones of the primary and secondary systems may 25 be obtained.

As will be noted in the drawings, the cooling element 90 is entirely insulated from the casting member 97 by the air space which surrounds the element 90. By this arrangement, the cooling element 90 does not apply its cooling action to the casting member 97. Thus it will be apparent that the cooling element may be used for maintaining low temperatures for freezing ice cubes and the like, and the secondary system may be used for cooling circulating air within the food storage compartment and that the temperature of the secondary system may be readily maintained at a temperature which provides for properly refrigerating the circulating air but above 40 the temperature which would cause the freezing of moisture contained in the circulating air which contacts with the casting 97. This avoids the necessity of periodically defrosting the element 45 which cools the circulating air.

As shown in Fig. 2, the cooling element 90 is provided with a liquid supply conduit 120 and a refrigerant vapor conduit 122 for supplying liquid refrigerant to and for withdrawing gaseous refrigerant from the element 90 respectively. In this particular embodiment of the invention, it is desirable that the cooling element 90 produce sufficient low temperatures for freezing and maintaining in the frozen condition substances in the trays 112. Consequently it is desirable that the operation of the primary system be controlled in accordance with temperatures prevailing in the cooling element 90. For this purpose I have provided a conduit 126 which may be connected to bellows 61. By this arrangement the operation of the primary system is controlled by changes in pressures in the element 90. Since the cooling element 90 is of the flooded type, changes in pressures and temperatures bear a direct relation with one another. Consequently the operation of the switch 60 in response to changes in pressure within the cooling element 90 will be the same as controlling the operation of the primary system in response to changes in temperature in 70 the cooling element 90. 65

Fig. 5 shows my invention in connection with a soda fountain with the syrup rail, which forms no part of this invention, being omitted. The apparatus comprises in general a cabinet 125 pro- 75

vided with an insulated ice cream compartment 127 and an insulated vaporizing chamber 130. Within the compartment 127 I have provided a plurality of open top sleeves 132 for receiving ice cream containers to be refrigerated. The sleeves 132 are cooled by a coiled cooling element 134 in contact therewith. The compartment 127 may be filled with a brine solution to provide a hold-over. Within the vaporizing chamber 130 I have provided a coil 137 for cooling circulating water, a body of liquid refrigerant the level of which I have indicated at 139, a body of congealable liquid 141 and a cooling element 143 for condensing evaporated refrigerant in the chamber 130.

15 The element 143 constitutes the primary system, and the chamber 130, refrigerant 139 and water 141 constitute the secondary refrigerating system. Liquid refrigerant is admitted to the cooling element 143 through conduit 150 under the control of an expansion valve 153. Refrigerant passes from the element 143 to the cooling element 134 and the gaseous refrigerant is withdrawn from the element 134 through a vapor conduit 154. Conduits 150 and 154 may be connected to the liquid refrigerant receiver 41 and the suction side of the compressor respectively. In this particular embodiment the secondary system serves to cool water in coil 137 in a like manner as the secondary system 28 cools the water in coil 27. In order to control the operation of the primary system so as to maintain predetermined low temperatures for maintaining the ice creams stored in compartment 127 in a frozen condition, I provide for controlling the operation of the primary system by means of a thermostatic bulb 156 which is placed in contact with the outlet end of the cooling element 134. This bulb is operatively connected to the bellows 61 for controlling switch 60.

40 In Fig. 4 there is shown a modified form of refrigerating apparatus for cooling circulating air in household refrigerators. The apparatus shown in this figure comprises in general a cabinet 160 having an insulated food storage compartment 162 and an insulated compartment 164. Within the compartment 164 there is disposed the primary refrigerating system which is herein shown as a body of solid CO₂ 166. An opening 168 is provided in the top wall of the cabinet to permit the insertion of the block of solid CO₂. The opening 168 is closed by a removable cover 169. Within the food storage compartment 162 and extending into the compartment 164 is a secondary refrigerating system 170. The secondary system comprises in general a U-shaped plate-type member 172 for cooling circulating air within the food storage compartment 162 and a flat plate-type member 174 within the compartment 164. The plate-type member 174 is arranged for supporting the block of dry ice so as to provide a good thermal contact therebetween. This portion of the secondary refrigerating system constitutes the condenser therefor. The cooling element 172 and the condensing member 174 of the secondary system are joined by a vertically extending conduit 176 which provides a small riser for evaporated refrigerant in the secondary system.

45 A quantity of refrigerant such as ether 180 is placed in the cooling element 172 and a small quantity of freezing fluid 182 which is insoluble in the refrigerant is put in the secondary system to fill the riser. When the proper temperature has been reached, the solution freezes and prevents the flow of evaporated refrigerant to the condenser 174 until the cooling element 172 warms

up sufficiently to melt the freezing solution. Thus it will be noted in this embodiment of my invention that I have provided a freezing solution within the secondary system which entirely closes off the passageway from the evaporating zone to the condensing zone. If desired, a cooling element similar to the element 98 shown in Fig. 3 may be substituted for the dry ice 166 for condensing the evaporated refrigerant in the secondary system when it is desired to make provision for freezing ice cubes or the like or when it is desired to provide an automatically operated primary refrigerating system.

Although only preferred forms of the invention have been illustrated, and those forms described in detail, it will be apparent to those skilled in the art that various modifications may be made therein without departing from the spirit of the invention or from the scope of the appended claims.

What is claimed is as follows:

1. The process of refrigeration which consists in evaporating and condensing a refrigerant in a closed system containing a body of liquid congealable and substantially unvaporizable at temperatures prevailing therein and utilizing the latent heat of fusion of the body of liquid when in a congealed form for condensing the vaporized refrigerant.

2. The process of refrigeration which consists in evaporating a volatile liquid refrigerant, contacting the liquid refrigerant with a body of fluid for congealing the fluid and subsequently utilizing the latent heat of fusion of the congealed body for condensing the vaporized refrigerant.

3. The process of refrigeration in a closed system which consists in evaporating a portion of a body of refrigerant, congealing a body of fluid within the system by such evaporation and subsequently utilizing the latent heat of fusion of the congealed body for condensing the vaporized refrigerant.

4. A closed refrigerating system comprising a vaporizing chamber containing a quantity of volatile refrigerant, means for condensing refrigerant evaporated in said chamber, and auxiliary condensing means for the evaporated refrigerant comprising frozen liquid within the vaporizing chamber congealed by evaporation and condensation of refrigerant in said chamber.

5. A refrigerating system comprising a vaporizing chamber containing a quantity of volatile refrigerant, means for condensing refrigerant evaporated in said chamber, and a body of liquid of lighter specific gravity than said volatile refrigerant within said chamber and congealable by evaporation of the refrigerant for controlling the amount of evaporated refrigerant condensed by said means.

6. A refrigerating system comprising a vaporizing chamber containing a quantity of volatile refrigerant, a body of liquid of lighter specific gravity in said chamber and congealable by evaporation of said refrigerant, and means above said body of liquid for condensing evaporated refrigerant.

7. A refrigerating system comprising means providing a chamber adapted to contain a quantity of volatile refrigerant, a body of water floating on top of the liquid refrigerant, and means for condensing evaporated refrigerant which passes through said body of water.

8. The process of refrigeration in a closed flow system which consists in establishing an evaporating zone and a condensing zone in open com-

munication with one another, and controlling the temperature of the evaporating zone by intermittently interrupting the flow of evaporated refrigerant from the evaporating zone.

5 9. A refrigerating apparatus comprising a primary refrigerating medium including a cooling zone, a secondary refrigerating system in heat exchange relation with said cooling zone for condensing evaporated refrigerant in the secondary system, and a congealable body of fluid immiscible with the refrigerant for controlling the evaporation of the refrigerant in the secondary system.

10 10. A refrigerating apparatus comprising a primary refrigerating system including a cooling zone, a secondary refrigerating system in heat exchange relation with said cooling zone for condensing evaporated refrigerant in the secondary system, and a liquid in said secondary system 15 adapted to become congealed by evaporation of said refrigerant and adapted to condense evaporated refrigerant after congelation of the liquid.

15 11. A refrigerating apparatus comprising a primary refrigerating system including a cooling zone, a secondary refrigerating system including a cooling zone and a portion in heat transfer relation with the cooling zone of the primary system for condensing evaporated refrigerant in said secondary system, and a body of fluid immiscible with said refrigerant and congealable at temperatures prevailing in said apparatus for maintaining a temperature differential between said cooling zones.

20 12. A refrigerating apparatus comprising a primary refrigerating system including a cooling zone, a secondary refrigerating system including a cooling zone and a portion in heat transfer relation with the cooling zone of the primary system for condensing evaporated refrigerant in said secondary system, and a congealable liquid in the secondary system of lighter specific gravity than said refrigerant for maintaining a temperature differential between said cooling zones.

25 13. A refrigerating apparatus comprising an intermittently operated primary refrigerating system including a cooling zone, a secondary refrigerating system in heat exchange relation with said cooling zone for condensing evaporated refrigerant in the secondary system, said secondary system including a cooling zone, a body of fluid congealable at temperatures prevailing in the apparatus for controlling the flow of evaporated refrigerant in the secondary system to the cooling zone of the primary system, and means responsive to changes in temperature of said body for controlling the operation of said primary system.

30 14. A refrigerating apparatus comprising an intermittently operated primary refrigerating system including a cooling zone, a secondary refrigerating system in heat exchange relation with said cooling zone for condensing evaporated refrigerant in the secondary system, said secondary system including a cooling zone, a body of liquid congealable by the evaporation of refrigerant in the secondary system for controlling the flow of evaporated refrigerant in the secondary system to the cooling zone of the primary system, and means responsive to changes in temperature in said primary cooling zone for controlling the operation of said primary system.

35 15. Refrigerating apparatus comprising, in combination, a primary refrigerating system including a cooling element, and a secondary re-

frigerating system disposed in heat transfer relation to the primary system for condensing evaporated refrigerant in the secondary system, said secondary system including a quantity of volatile refrigerant and a body of congealable liquid which is nonmiscible with said volatile refrigerating for maintaining a temperature differential between the primary and secondary systems.

40 16. A refrigerating system including a condensing zone and an evaporating zone, a quantity of volatile refrigerant disposed in said evaporating zone, and a body of water floating on the surface of said refrigerant.

45 17. A secondary refrigerating system including a condensing zone and an evaporating zone, a quantity of volatile refrigerant disposed in said evaporating zone, and a body of congealable liquid which is nonmiscible with the refrigerant floating on the surface of the refrigerant to vary the temperatures between the condensing and evaporating zones.

50 18. Refrigerating apparatus comprising, in combination, a tank containing a quantity of liquid refrigerant and a body of liquid in contact with the refrigerant and congealable by evaporation of said refrigerant, and a cooling element for condensing the evaporated refrigerant.

55 19. Refrigerating apparatus comprising heat absorbing means adapted to be placed in a refrigerator for cooling circulating air therein and for freezing substances, including a metallic shell, a low temperature cooling element disposed in said shell, said shell containing a quantity of liquid refrigerant, and a body of liquid immiscible with said refrigerant contained in said shell and adapted to congeal for maintaining a temperature differential between said shell and said element.

60 20. The process of refrigeration which comprises, contacting a congealable fluid with a volatile liquid refrigerant for congealing at least a part of said fluid, simultaneously condensing the vaporized refrigerant, returning the condensed refrigerant to the source of liquid refrigerant, and subsequently utilizing the latent heat of fusion of the congealed fluid for condensing the vaporized refrigerant.

65 21. The process of refrigeration which comprises, contacting a liquid with a body of volatile liquid refrigerant, simultaneously condensing the vaporized refrigerant and returning the condensed refrigerant to the liquid, and subsequently utilizing the ice which is frozen by such process as a medium for condensing vaporized refrigerant.

70 22. The process of refrigeration which comprises, cooling a liquid substance by simultaneously contacting the liquid substance with a body of volatile liquid refrigerant and condensing vaporized refrigerant and returning the condensed refrigerant to the liquid substance, and subsequently utilizing the substance as a medium for condensing vaporized refrigerant.

75 23. The process of refrigeration which comprises, cooling a liquid which is congealable by cooling the same by simultaneously contacting the liquid with a body of volatile liquid refrigerant and passing the vaporized refrigerant through the congealable liquid and condensing the vaporized refrigerant and returning the condensed refrigerant to the source of liquid refrigerant, and utilizing the congelation characteristic of the congealable liquid for controlling the vaporization of the liquid refrigerant.

80 24. A refrigerating system including a condensing zone and an evaporator zone, a quantity of

methylene chloride disposed in said evaporating zone, and a body of water floating on the surface of said methylene chloride.

25. Refrigerating apparatus comprising, in combination, a tank containing a quantity of methylene chloride, a cooling element disposed in the upper part of said tank, a fluid circulating conduit disposed in the lower part of said tank in contact with said methylene chloride, and a body of water floating upon said methylene chloride for maintaining a temperature differential between said body of methylene chloride and said element.

26. A cooling unit for refrigerators comprising two evaporators, one within the other and spaced apart, and means for maintaining a higher temperature within the outer evaporator than within the inner evaporator.

27. A cooling unit for refrigerators comprising an outer flooded evaporator and an inner flooded evaporator arranged within and spaced from said outer evaporator, and means for maintaining said outer evaporator at a temperature higher than the freezing point of water, and for maintaining said inner evaporator at a temperature sufficiently low for freezing purposes.

28. A cooling unit for refrigerating machines comprising an outer evaporator, an inner evaporator within and spaced from said outer evapo-

rator, and differential pressure means for maintaining said outer evaporator at a higher temperature than said inner evaporator.

29. A cooling unit for refrigerating machines comprising an outer evaporator and an inner evaporator spaced from said outer evaporator, means for maintaining the temperature of said outer evaporator periodically above and below 32° F., and means for maintaining the temperature of said inner evaporator sufficiently low for freezing purposes.

30. A cooling unit for refrigerating machines comprising an outer evaporator, a second evaporator within and spaced from said outer evaporator, means for supplying refrigerant to said second evaporator, means for removing vaporized refrigerant from said second evaporator, and means including refrigerant flow resistance means for maintaining said outer evaporator at a higher temperature than said second evaporator.

31. In combination, a refrigerator cabinet and a cooling unit within said cabinet and comprising two evaporators, one within the other and spaced apart, and means for maintaining a higher temperature within the outer evaporator than within the inner evaporator.

LAWRENCE A. PHILIPP.
